[57] CLAIM

The ornamental design for defense flasher housing, as shown.

DESCRIPTION

FIG. 1 is a front perspective view showing my new design for a defense flasher housing;

FIG. 2 is a perspective view thereof taken from the opposite side from the view of FIG. 1;

FIG. 3 is a top plan view thereof; and

FIG. 4 is a bottom view thereof.

The broken line showing of the flash cube is for illustrative purposes only and forms no part of the claimed design.

FIG. 1.

FIG. 2.

FIG. 3.

FIG. 4.
